C. K. MARSHALL, OF NEW ORLEANS, LOUISIANA.

Letters Patent No. 79,137, dated June 23, 1868; antedated June 6, 1868.

METALLIC HORSE-COLLAR.

The Schedule referred to in these Letters Patent and making part of the same.

TO ALL WHOM IT MAY CONCERN:

Be it known that I, C. K. MARSHALL, of New Orleans, parish of Orleans, and State of Louisiana, have invented certain new and useful Improvements in Metallic Horse-Collars; and I do hereby declare that the following is a full, clear, and exact description of the same, reference being had to the annexed drawings, and to the letters of reference marked thereon, in which—

Figure 1 is a front view of my metallic horse-collar, showing hinge-fastening at bottom and strap at top.
Figure 2 is also a front view of my metallic horse-collar, showing another mode of fastening the same at bottom.

Figure 3, section, at x x , of fig. 1, showing the strengthening-brace.

Figure 4, section, at y y , of fig. 2, showing the collar filled with wood or other material.

Figure 5, another device for hinge-fastening.

Figure 6, another device for strap-fastening.

I am aware that various attempts have been made to supersede the use of leather, in whole or in part, in the manufacture of horse-collars, with a view to lessen their expense, and also to prevent the galling of the horse. To obtain those desirable advantages, collars have been made of felt or felted cloth, and more recently duck-cloth has been used for the same purpose.

Practical experience has demonstrated the fact that the use of such materials does not answer the purpose, as they possess still greater disadvantages than are met with in the ordinary leather collar.

It is well known that all the collars now in use, with scarcely a single exception, are constructed of materials that will freely absorb the perspiration and vapor from the horse, and this, instead of tending in any degree to lessen the chafing and galling of the horse, experience proves is the very cause which most generally produces it. Moreover, in rainy weather the water will penetrate all the materials now in common use, and the straw will become completely saturated, and being closely packed in the collar, will retain the water for a long time.

Among the chief causes which produce galling is the working of the stuffing of the collar into hard knots or "bunches," so as to render the surface of the collar "lumpy," or more unyielding at one point than at another, and it is well known that this "lumpy" condition of the stuffing will be produced much sooner when liable to become wet, either from perspiration or rain, than from any other cause.

Furthermore, the stuffing, in a wet or damp condition, rots rapidly, and the pressure of the hames on the collar will tend to squeeze the water from the rotten straw, through the collar, thereby staining it, and by the dampness of the straw also cause the material to rot.

My improvement obviates all of the foregoing objections, can be manufactured cheaper than any collar now in use, and is also entirely practical.

My invention consists, first, in constructing a horse-collar entirely of metal; second, in introducing a system of bracing between the metallic plates; and, third, in attaching to the collar "rein-eyes" and "trace-clips," so as to dispense entirely with the use of hames.

My collar being constructed, as it is, entirely of metal, can be made exceedingly light. It is cheaper than any material now used for the purpose. It will sustain an immense draught, for it is constructed on the well-known principle of the "braced double arch." It is impervious to rain. It does not absorb the perspiration from the horse. It does not gall the animal, no matter how constant the use or heavy the pull. Its surface being perfectly smooth and as unyielding at one point as at another, the great cause of chafing and rubbing the horse is removed.

To enable others skilled in the art to which my invention is applicable to make and use the same, I will proceed to describe its construction and operation.

A A are metal cylindrical plates, of the form shown in figs. 1 and 2, and are of a shape which enables them exactly to conform to the contour of the neck and shoulders of the animal. The plates may be made of any suitable metal, and may be made from the sheet, or cast.

When made of cast metal, they are formed precisely as any other ordinary casting. When made of sheet metal, they may be formed in moulds with dies, or "struck up" on any of the machines now used for this class of work. The rear plates are exact counterparts of the front plates A A, and they may be united by riveting, brazing, soldering, or seaming. These plates A A, at their lower ends, are united together by a hinge or link, *a*, universal joint, strap, and eye, or any other convenient means. They are left free at their upper ends, and can be united, when desired, by a strap, *b*, or any other convenient means.

To the front plates A A, I attach, by rivets or screws, as shown in fig. 4, or other suitable means, "rein-eyes," *c c*, and trace-clips *d d*, which enables me to dispense entirely with hames, and with them all the annoyances and disadvantages connected with their use. The front and rear plates, when brought together and united, form, as it were, a hollow cylinder, as clearly shown in figs. 3 and 4.

When the same is deemed desirable, I introduce at different points a double T-(I)-headed brace, *e*. The cylindrical opening between the plates may be filled with wood, or the space may be stuffed with any suitable material, for example, the lignine flour patented to me, November 12, 1867. When articles of such character, however, are used, the same must be thoroughly packed between the plates. In very severe weather, a thin sheet of leather may be attached to the under side of the collar, so that when the collar is applied to the neck of the animal, the metal will not come in immediate contact therewith.

The upper plate A may be either plain or corrugated.

Collars constructed of sheet metal are susceptible of the highest degree of ornamentation, and may be faced with patent leather, or they may be galvanized and plated.

It will readily occur to any one familiar with the art that collars constructed on my plan may be made beautiful and artistic in the extreme.

Having thus fully described my invention, what I claim therein as new, and desire to secure by Letters Patent, is—

1. A metallic horse-collar, constructed substantially as described, and for the purpose specified.
2. Bracing the metallic plates, of which the horse-collar is formed, substantially as described, and for the purpose specified.
3. The combination of the plates A A, "rein-eyes" *c c*, and trace-clips *d d*, when the same are constructed and arranged substantially as described.

In testimony whereof, I have signed my name to this specification in the presence of two subscribing witnesses.

C. K. MARSHALL.
